Attorney

UNITED STATES PATENT OFFICE.

SAMUEL BERGSTEIN, OF MIDDLETOWN, OHIO, ASSIGNOR TO THE INTERSTATE FOLDING BOX COMPANY, OF MIDDLETOWN, OHIO.

PAPER BOX AND THE LIKE.

Application filed December 20, 1926. Serial No. 155,841.

This invention relates to improvements in paper cartons, or the like.

In the accompanying drawings which serve to illustrate the invention:

5 Fig. 1 is a view illustrating the improved construction of the box blank;

Fig. 2 is a view illustrating a tube formed from the blank shown in Fig. 1;

10 Fig. 3 is a sectional view of the completely formed carton.

Figs. 4 and 5 are views illustrating modifications.

The invention relates particularly to improved joint construction in paper cartons, 15 paper boxes, and articles of similar construction.

Containers of this character used for bulky or heavy articles frequently develop weakness along the adhesive joints, the joints 20 breaking open under the outward pressure of the contents, thus impairing or destroying the value of the containers for protecting the contents.

This condition is caused, where heavy 25 paper stocks are used for making the containers, by the stiffness of the stock, more especially where the edges of the material overlap at the joints, thus lacking flexibility to adapt the joints to yield to the manufacturing stresses or to the pressure of the contents when the containers are filled, with the result that the joints break open or split 30 along the adhesive seams as stated.

The difficulty is overcome by the improved 35 joint construction comprised in the invention which, without adding materially to the cost of production, results in containers which are free of this weakness.

The improved joint as illustrated in the 40 drawings consists of a double overlap joint extended on opposite sides of the medial folding line 1, extended longitudinally of the joint.

The joint as here shown is wider than ordinary overlap joints thus providing for the outer overlapping portion 2 to be extended over and beyond the medial line of the joint. The inner overlapping portion 3 in like manner extends over and beyond the medial line

in the opposite direction, a corner of the box 50 as shown in Fig. 3 being formed on the medial line.

The main feature of the improvement consists in the serrated edge 4 of the inner portion of the joint which acts to render the 55 joint yieldable to the pressure thereon by the contents, or from any source, without causing the joint to split open.

The joint as herein shown and described 60 merely serve for illustrating the improved construction. It will be obvious that both the inner and outer overlapping portions may be serrated to effect greater flexibility 65 of the joint, also that the serrations may be used on single overlapping joints with like effect, the several modifications being illustrated in Figs. 4 and 5. In Fig. 4 a double overlapping joint is shown with double serrated edges. In Fig. 5 a single joint is shown with serrated edge. 70

It will be obvious that various forms of serrations may be used for practicing the invention.

Having described my invention, I claim:

1. Paper articles of manufacture, including an overlapping adhesive joint comprising serrations along the edge of one of the overlapping portions. 75

2. Paper articles of manufacture, including an overlapping adhesive joint comprising portions extended oppositely one relative 80 to the other laterally of the longitudinal medial line of the joint, and serrations formed along the edge of one of said portions.

3. Paper articles of manufacture, including an overlapping adhesive joint comprising serrations formed along the opposite overlapping edges of the joint. 85

4. Paper articles of manufacture, including an overlapping adhesive joint, the longitudinal medial line of the joint coinciding with a corner of the article, the overlapping portions being extended over and oppositely laterally of the medial line, and serrations formed along the edge of one of said portions. 90

In testimony whereof, I affix my signature.

SAMUEL BERGSTEIN.
